UNITED STATES PATENT OFFICE.

CLEN S. HUMPHREY, OF BROOKLYN, NEW YORK.

DESIGN FOR A RECEPTACLE.

53,912.

Specification for Design.

Patented Oct. 7, 1919.

Application filed May 23, 1919. Serial No. 299,350. Term of patent 7 years.

To all whom it may concern:

Be it known that I, CLEN S. HUMPHREY, a citizen of the United States, and a resident of the city of New York, borough of Brooklyn, in the county of Kings and State of New York, have invented a new, original, and ornamental Design for a Receptacle, of which the following is a specification, reference being had to the accompanying drawing, forming part thereof.

Figure 1 is a side elevation of a receptacle embodying my new design.

Fig. 2 is a plan view thereof.

In plan, one side of the receptacle forms an arc of a circle and the other side part of an octagon. This receptacle is to be primarily for toilet and other powders, also for tea, coffee and other commodities.

I claim:

The ornamental design for a receptacle, substantially as shown and described.

CLEN S. HUMPHREY.
